J. E. SARGENT

MEANS FOR SUPPLYING WATER

Filed Sept. 19, 1921

INVENTOR:

John Ellery Sargent

BY *Arthur H. Ewald*,

ATTORNEY.

Patented Nov. 17, 1925.

1,561,798

UNITED STATES PATENT OFFICE.

JOHN ELLERY SARGENT, OF MORGAN, KENTUCKY, ASSIGNOR OF ONE-HALF TO W. M. NORTHCUTT, OF MORGAN, KENTUCKY.

MEANS FOR SUPPLYING WATER.

Application filed September 19, 1921. Serial No. 501,653.

To all whom it may concern:

Be it known that I, JOHN ELLERY SARGENT, a citizen of the United States, and resident of Morgan, in the county of Pendleton and State of Kentucky, have invented 5 certain new and useful Improvements in Means for Supplying Water, of which the following is a full, clear, and exact description, reference being had to the accompanying drawings, forming a part of this 10 specification.

This invention relates to means for supplying water, and has particular reference to the provision of means whereby water is 15 distributed under pressure.

The principal object of this invention is to provide water supplying means for distributing water to the various points in buildings, barns, etc., where required, comprising in part a tank adapted to be located 20 under water in a well, spring or other source of supply, where the same is not subject to freezing temperature.

A further object of this invention is to 25 provide, in connection with a tank located as above set forth, valve mechanism adapted for automatic operation so that a supply of water is at all times maintained inside the tank.

Another object of this invention is to 30 provide in a tank of the type mentioned a separate compartment in which a supply may be maintained under pressure even after the water in the main tank has become 35 exhausted.

Further objects of the invention will appear from the following detailed description thereof.

In the drawings:

40 Figure 1 is a sectional view of the water supplying means constructed in accordance with this invention.

Figure 2 is a cross-section on line 2—2 of Fig. 1.

45 Figure 3 is a plan view of the invention, a part of the upper portion of the tank being broken away so as to disclose the interior structure.

Figure 4 is a longitudinal section of the 50 valve mechanism on an enlarged scale.

Figure 5 is a sectional view of one of the valve mechanisms.

The numeral 1 indicates a tank, preferably of metal construction, and oval in

cross-section as shown in Figure 2. The 55 tank 1 may be of any suitable size, preferably of such dimensions as to contain approximately from 10 to 30 gallons. The tank 1 is provided, near one end, with a partition 2, which divides the tank into compartments 3 and 4 respectively. A pipe 5, located in compartment 4, communicates through the partition 2, near the bottom of the tank, with compartment 3. The pipe 5 extends upwardly in compartment 4 to a 60 point near the top thereof. The upper end of the pipe 5 is provided with a cage 6, within which a ball valve 7 is located, said valve being arranged to seat in the end of the pipe. The end wall of compartment 3 is 65 provided with an inlet pipe 8. Slidably mounted in the pipe 8 is a cup-shaped valve 9 provided with prongs 10. The valve 9 is securely mounted on a valve rod 11. Secured on the rod 11, adjacent the inner 70 end of the valve 9, is a rubber, leather, or other flexible washer 12. Securely mounted on the rod 11 inside of and contiguous to the washer 12 is a pressure cup 13. As 75 illustrated in the drawings, two nuts 14 secure the valve 9, the washer 12, and the pressure cup in the specified assembly on the rod 11.

Pivottally mounted in a bracket, or brackets, 15, inside the tank 1, are arms 16 and 17 which extend upwardly in the tank to points slightly above the valve rod 11, and then converge away from the valve, as shown in Fig. 3, the free ends of the arms being secured to a float 18. A cross-bar 19 is secured between the arms 16 and 17 and is slidable on the valve rod between nuts 19^a. The outer end of the pipe 8 is provided with a housing 20, having bearings 21 for the outer end of the rod 11. The housing 20 is also provided with a socket 22 for a spring-pressed ball 23, which is adapted to engage respectively in depressions 24 and 25 in the rod 11.

The tank 1 is provided with an outlet 26, which communicates with the chamber 4 of the tank. Pipe 27 distributes water from the chamber 4 to various desired points, as, for instance, in the kitchen and bath room of a farm residence and other places where water is required.

Tank 1 is provided with an inlet 28, communicating with the chamber 3,

through which air pressure is maintained in the tank by means of a suitable air pump conveniently located.

The operation of the device is as follows:

- 5 The tank, with the various mechanisms described, is submerged in a well, spring, stream or other source of water supply. Water is admitted into the tank through the pipe 8 by the automatic valve. When
- 10 the water in the tank falls to a certain point, the falling float draws the rod 11 outwardly, thus withdrawing the valve 9 from the inner end of the pipe so that water may pass inwardly through the pipe
- 15 and the openings between the prongs 10 of the valve. In this position the ball 23 engages the notch 25 in the rod. As the water in the tank rises the float causes the bar 19 to exert an outward pressure on the rod 11. By reason of the friction of the spring-pressed ball 23, however, the valve does not immediately close, but the water is permitted to continue its inward flow until the tank is approximately full, at which
- 25 time the outward pressure on the rod is so great as to overcome the friction and cause the valve to close suddenly, the pressure cup 13 compressing the washer 12 into the inner end of the pipe 8. Air pressure
- 30 is maintained inside the tank through the inlet 28 by means of an air pump suitably located. This pressure causes water to flow through the pipe 5 into compartment 4, and thence outwardly through pipe 27 to the
- 35 various points of distribution where it is drawn upon in the ordinary manner when required. By reason of the pipe 5 and valve 7 a supply of water under pressure is maintained in the compartment 4, even
- 40 when the supply in compartment 3 is exhausted to the point of opening the valve, when the pressure in compartment 3 is, of course, relieved, the valve 7 closing when the pressure in compartment 4 exceeds that in compartment 3. The cup 13 presses against washer 12 effectively closing the automatic valve when the float is raised and air pressure is maintained in the tank.
- 45 When the valve is closed the ball 23 engages in notch 24 and thus prevents the

opening of the automatic valve until the water has become virtually exhausted from compartment 3 of the tank.

As will be seen, a suitable tank and automatic mechanism are thus provided for supplying water under pressure to desired points of distribution. It is also obvious that this tank, which receives its pressure from any point of convenient location on the premises, may be submerged in any suitable natural water repository or source of supply, to such depth that the same is safe against freezing or other sources of damage, the supply of water being automatically maintained inside the tank by reason of the valve mechanism described.

Having thus fully described my invention, what I claim as new and desire to secure by Letters Patent is:

1. In a device of the character specified in combination with a tank adapted to be submerged in liquid in a repository, automatic valve mechanism arranged to be operated when the liquid in the tank falls below a certain level, and means for maintaining pressure in said tank to force liquid therefrom, a secondary chamber, means of communication between said tank and secondary chamber so that liquid in the tank is forced, under pressure, into said secondary chamber, and a valve arranged to close when the pressure in the tank falls below that in said secondary chamber.

2. In a device of the character specified, in combination with a tank adapted to be submerged in liquid in a repository, automatic valve mechanism arranged to be operated when the liquid in the tank falls below a certain level, and means for maintaining pressure in said tank for the distribution of the liquid therefrom, a secondary chamber in said tank, means whereby said secondary chamber communicates with the principal chamber in said tank so that liquid in the principal chamber is forced, under pressure, into said secondary chamber, and a valve arranged to close when the pressure in the principal chamber falls below that in said secondary chamber.

JOHN ELLERY SARGENT.
